UNITED STATES PATENT OFFICE.

ANDREW B. LIPSEY, OF WEST HOBOKEN, NEW JERSEY, ASSIGNOR TO
WILLIAM BELL, OF NEW YORK, N. Y.

GAS-BURNER.

SPECIFICATION forming part of Letters Patent No. 291,480, dated January 1, 1884.

Application filed June 12, 1883. (No model.)

To all whom it may concern:

Be it known that I, ANDREW B. LIPSEY, of West Hoboken, in the county of Hudson and State of New Jersey, have invented a certain 5 new and useful Improvement in Gas-Burners, of which the following is a specification.

This improvement consists in a novel method of suspending a gas-burner, and it includes a means whereby the heating of the gas before 10 its arrival at the burner tip or tips will be effected.

In the accompanying drawings, Figure 1 is a central vertical section of a gas-burner and appurtenances embodying my improvement. 15 Fig. 2 is a horizontal section of the same, and Fig. 3 is an inverted plan or bottom view thereof.

Similar letters of reference designate corresponding parts in all the figures.

20 A designates an annular burner-tip having apertures for the escape of jets of gas at its apex, and supported by a number of hollow arms, *a*, which extend to it from a central body-piece, *b*, and conduct gas to it from the 25 said body-piece. In the body-piece *b* of the burner-tip is a central cavity, into which the gas is conducted. The gas which is to be used in the burner is supplied from any suitable source through a pipe, *B*. This pipe *B* is 30 screwed into a disk, *C*, and communicates with a similar pipe, *D*, also screwed into said disk, but extending downwardly therefrom. The pipe *D* is open at the lower end and extends nearly to a second disk, *E*. A pipe, *F*, 35 considerably larger than the pipe *D*, is screwed into the disk *E* in such position as to be concentric with the pipe *D*. A shell, *G*, extends between the disks *C E*. As shown, it enters a groove in the under side of the disk *C* and 40 screws on the exterior of the disk *E*.

H designates a pipe extending downwardly from the disk *E*, and, as here shown, it is secured thereto by being screwed onto a downwardly-extending flange. Passages or ducts 45 *c* extend through the disk *E* and establish communication between the space outside the pipe *F*, within the shell *G* and the pipe *H*. The lower end of this pipe *H* is connected with the central cavity in the body-piece of 50 the burner-tip *A* by means of a taper pipe, *I*.

The pipe *I* is shown as being screwed into the pipe *H* and upon the exterior of the body-piece of the burner-tip.

Arms *J*, adjustably secured to certain of the arms *a* of the burner-tip, serve to support a 55 chimney, *K*, which is shown as cylindrical in shape, and may be made of glass. The arms *J* are longitudinally slotted, and are secured to the arms *a* by screws passing through their slots and entering the arms *a*. This chimney 60 *K* extends above the lower portion of the shell *G*.

L designates a number of pipes extending from the disk *E* to the disk *C*. These pipes are shown as being screwed into the disk *E*, 65 but they are preferably expanded into the disk *C*. They secure the disks together. These pipes are arranged in a circular row or series close to the interior of the shell *G*. Gas, entering the pipe *B*, passes downwardly to and 70 through the pipe *D*, thence into the pipe *F*, and thence upwardly through this pipe *F* into the space inclosed by the disks *C E* and the shell *G*. From the shell *G* the gas passes through the apertures *c* into the pipe *H*, thence 75 into the pipe *I*, thence into the body-piece of the burner, and thence through the arms *a* into the burner-tip. The air necessary to support combustion enters between the arms *a* to the space encircled by the burner-tip, and between the arms *J* to the space which is between the burner-tip and the chimney *K*. The 80 products of combustion pass up around the pipe *H* and heat the gas therein. Ascending above the pipe *H* they enter the pipes *L*, and 85 thence escape into the atmosphere. In passing through the pipes *L* the escaping products of combustion heat the gas which is in the shell *G*.

Around the pipe *H* is a piece of incandescent material—such as porcelain or abestus. It is shown as externally of an inverted conical form, so that it will form a deflector for throwing air against the interior of the flame.

A circular series of burner-tips may be used 90 in lieu of a single annular burner-tip.

I have obtained Letters Patent for improvements in gas-burners, No. 278,568, dated May 29, 1883, and No. 282,337, dated July 31, 1883. I have also made other improvements in gas- 95 100

burners, for which I have filed applications for Letters Patent on November 4, 1882, Serial No. 77,087; June 6, 1883, Serial No. 97,245; July 2, 1883, Serial No. 99,750, and July 11, 5 1883, Serial No. 100,490.

In my present application I do not desire to claim anything that is covered by my Letters Patent and applications above referred to.

By the arrangement of the pipes D F and 10 the shell G, I cause the gas to pass a greater distance while subjected to heat from the escaping products of combustion than in my other improvements, because the gas has to descend to the bottom of the pipe D, then as- 15 cend to the top of pipe F, and finally descend to the bottom of the shell G, thereby passing three times a distance equal nearly to the length of the shell G before escaping into the pipe H. By making the pipe H nearly as 20 large as the annular burner-tip or series of burner-tips and leaving it uninterrupted by any pipe passing through it I provide a chamber of large capacity through which the gas passes sluggishly, and in which the gas is 25 finally heated to a high degree before passing to the burner tip or tips. It will therefore be seen that I provide a long passage consisting of the intercommunicating pipes D F and the shell G, in which the initial heating of the gas 30 will be performed, and a large chamber through which the gas will pass so slowly that its final heating will be effectively performed. The pipes H and I serve the additional purpose of a support for the burner tip or tips.

35 What I claim as my invention, and desire to secure by Letters Patent, is—

1. The combination, with the upwardly-ex-

tending annular burner-tip A or a circular series of burner-tips, of the downwardly-extending gas-supply pipe D, and the pipe H I, 40 communicating with the pipe D and extending downward to a central body-piece, whence gas is supplied to the burner tip or tips, and made much larger than the pipe D, so as to form a chamber wherein the gas will be 45 heated by the flame and ascending products of combustion, substantially as specified.

2. In a gas-burner, the combination of a gas-supply pipe by which the burner is to be suspended, and which is open at the lower 50 end, a second pipe of larger size surrounding the gas-supply pipe, closed at the lower end and open at the upper end, a shell surrounding said second pipe and communicating with the open upper end thereof, a third pipe ar- 55 ranged below and communicating with said shell, and an annular burner-tip, or a circular series of burner-tips supported by the last-mentioned pipe, and to be supplied with gas therefrom, substantially as specified.

3. The combination, with an annular burner-tip, or a circular series of burner-tips, of the pipe B, the shell G, connected to the disks C E, a pipe establishing communication between the space inclosed by the said shell G 65 and a central body-piece, whence gas is supplied to the burner tip or tips, a chimney, and the pipes L, arranged within the shell G, substantially as specified.

ANDREW B. LIPSEY.
